UNITED STATES PATENT OFFICE.

ELEONORA FLANAGAN, OF PORTLAND, OREGON.

DESIGN FOR A WALL-POCKET OR SIMILAR ARTICLE.

No. 38,781.

Specification for Design.

Patented Sept. 3, 1907.

Application filed May 6, 1907. Serial No. 372,288. Term of patent 3½ years.

To all whom it may concern:

Be it known that I, ELEONORA FLANAGAN, a citizen of the United States, residing at Portland, in the county of Multnomah and State of Oregon, have invented a new, original, and ornamental Design for Wall-Pockets or Similar Articles, of which the following is a specification, reference being had to the accompanying drawings, forming part thereof.

The figure is a front elevation of a wall pocket, or similar article, showing my new design.

I claim:—

The ornamental design for a wall pocket, or similar article, as shown.

ELEONORA FLANAGAN.
